E. E. HILLYER.

HEADLIGHT.

APPLICATION FILED JAN. 2, 1920.

1,386,059.

Patented Aug. 2, 1921.

UNITED STATES PATENT OFFICE.

ERNEST E. HILLYER, OF PORT RICHMOND, NEW YORK.

HEADLIGHT.

1,386,059.

Specification of Letters Patent.

Patented Aug. 2, 1921.

Application filed January 2, 1920. Serial No. 348,955.

To all whom it may concern:

Be it known that I, ERNEST E. HILLYER, a citizen of the United States, residing at Port Richmond, county of Richmond, State 5 of New York, have invented certain new and useful Improvements in Headlights, of which the following is a full, clear, and exact description.

This invention relates to improvements in 10 head lights for motor vehicles. The object of my invention is to provide a head light device which is adjustable in order that the rays of light emanating therefrom can be directed upon a road wherever desirable and 15 maintained in such adjusted position. Owing to the diversity of existing laws governing headlights, it is almost impossible to meet the requirements of different States by means of a fixed or unchangeable anti-glaring device. In some States more light upon the 20 road, at each side of the front end of a motor vehicle, is required than in other States, also the distance ahead of the vehicle at which the rays shall strike the road varies 25 with different States, to say nothing of various other requirements.

My invention consists of a combination 30 of an adjustable reflector carrying a bulb, and a lens, a portion of which is rendered translucent or shrouded, preferably the upper portion. By adjusting the reflector the light rays can be altered with respect to the 35 line of cut off of the transparent portion of the lens; hence the distance at which the light will strike the road ahead of the vehicle can be changed at will. The amount of light cast on the road at the side of the vehicle, and ahead of same, can be altered by 40 adjusting the reflector in a vertical plane.

40 In the drawing, which forms part of this specification:—

Figure 1 is a sectional view of a head light embodying my improvements;

Fig. 2 is a front view thereof;

45 Fig. 3 is a rear view thereof;

Fig. 4 is an enlarged fragmentary sectional plan view, the section being taken on line 4—4 in Fig. 1; and

50 Fig. 5 is an enlarged fragmentary vertical sectional view, the section being taken on line 5—5 in Fig. 1.

As before stated, the chief object of my invention is to provide a head light that may be adjusted to meet the laws of different 55 States as well as to provide an anti-glaring

device of this nature by blanking off the upper portion of the lens. The partly translucent lens forms an important part of my invention as by its employment, in combination with an adjustable reflector, I am able 60 to obtain the adjustments desired. As herein embodied, my invention consists of a casing 6 containing an adjustable reflector 7, which carries a lamp bulb 8, and a lens 9 a part 10 of which is shrouded or rendered 65 translucent by frosting or coloring same. The upper portion of the lens may be colored green, amber or any other desired color. The reflector 7 is freely suspended within the casing 6, that is to say, not secured to same 70 but is connected to the casing by adjustable elements. The reflector, by means of the adjustable elements, may be raised or lowered vertically, moved to any desired angular position, within a certain limit, that is to say, 75 tilted forward or backward, or rotatably adjusted horizontally. When the reflector is raised or lowered, the rays of light cast off adjacent the axis of the reflector, said rays being indicated by the arrow 80 13 in Fig. 1, will be altered with respect to line of cut off of the transparent portion 12 of the lens, said line of cut off being indicated by 13^a. By means of the vertical adjustment of the reflector, the light bulb 8 85 can be so positioned as to reduce glare to a minimum, for it will be remembered that glaring rays will not pass through the shrouded portion 10 of the lens. Should the vertical adjustment imparted to the reflector 90 be such as to reduce glare to a minimum, but destroy the desired road illumination, the reflector can be tilted forward or backward to cast the rays upward or downwardly with respect to the line of cut off 13^a. In fact both 95 vertical adjustment and tilting will be resorted to to obtain the desired results. To alter the light with respect to the sides of the road, the reflector 7 will be rotated horizontally. All of the adjustments above referred to will be accomplished by manipulation of certain elements located exteriorly 100 of the casing 6. To obtain the adjustments various devices may be employed, but to adjust the reflector vertically, I have in this 105 instance illustrated a rod 14 which is pivotally connected to the reflector as at 15 and held in position by a plate 16. The rod 14 passes loosely through a block 17 and is threaded for a portion of its length as at 18. 110

The threaded portion of the rod is engaged by a thimble 19 having a threaded bore, as is evident, the exterior of the thimble being also threaded to receive a lock-nut 20. The 5 thimble 19 carries a head 21 having a convex surface 22 to engage the casing adjacent a slot 23 in said casing. To adjust the reflector vertically, the lock-nut 20 will be loosened and the thimble rotated to raise or 10 lower the reflector. After the reflector is adjusted the lock-nut 20 will be fastened. To tilt the reflector, I provide a threaded pin 23^a, which, at its inner end, engages the block 17, the connection being of the ball 15 and socket variety, indicated by 24. The pin 23^a is engaged by a threaded thumb-nut 25 rotatably supported by the casing 6, a lock nut 26 being employed to firmly fasten the thumb-nut 25. To tilt the reflector, the 20 lock-nut 20 will be loosened and thumb-nut 25 manipulated to move the lower end of reflector 6 in or out, as indicated by arrows 27 and 28. The slot 23 permits of the shifting of the rod 14 forwardly or backwardly 25 and the convex surface of the head 22 permits of a firm securement of the thimble 19 to the casing. To tilt the reflector a pivotal point is essential. In this instance the pivotal point is located at 29, said point being 30 the point of connection of a link 30 to said reflector, the connection being loose or having a little play. The other end of link 30 is pivotally connected, in this instance, to a crank-arm 31 extending from a stub-shaft 35 32 (see Fig. 5), rotatably supported by casing 6. The stub-shaft 32 carries a thumb-nut 33 and a lock nut 34. When stub shaft 32 is rotated, either forward or backward, the reflector 7 will be rotated upon rod 14 40 at the point 15. To cast the rays more to the center of a road or more to the side of a road, the stub-shaft 32 will be rotated accordingly and fastened by the lock-nut 34 after the desired adjustment has been made. Any 45 one of the adjustments mentioned can be obtained independently or in other words obtained without necessarily disturbing each other. In other words, after a desired vertical adjustment has been made, the reflector 50 can be tilted or rotated without destroying the vertical adjustment or vice versa. To focus the bulb, I provide the casing with a hand hole 35 in the rear thereof and provide a cap 36 for said hand hole. As the bulb is 55 carried by the reflector and as the reflector is movable, it is necessary to provide some means by which the bulb can be focused. In this instance, I provide the said hand hole 35 through which a hand can be passed to 60 manipulate the bulb to focus same. A binding screw 37 may be employed to secure the bulb after it has been focused. A person knowing the laws regarding head light of a State he is about to enter or resides in, can 65 adjust the reflector to cast rays of light to

meet said laws after which the adjustment can be maintained by the different locking elements.

My invention also possesses the advantage of enabling a person to properly adjust his 70 lights, as it frequently occurs that head lamps or casings are placed out of position by the manufacturer and one lamp will point upwardly or downwardly more than the other or inwardly or outwardly more than 75 the other. By means of my adjustable features the position of the casing is entirely immaterial and I can adjust the reflectors to meet any requirement within reason. When making most of the adjustments, it 80 will be understood that most of the locking nuts will be loosened to permit the parts locked thereby to move to accommodate the adjustment desired. To adjust the reflector vertically, it will not be necessary to loosen 85 the lock nut 26 as rod 14 will slide within block 17 and there will be enough to slack at the pivotal point 29 to permit the reflector to move. All adjustments will be but slight. 90

Having described my invention, what I claim and desire to secure by Letters Patent is:—

1. In a head light, a casing, a vertically disposed vertically adjustable movable support carried by the casing, a reflector rotatably mounted upon said support, adjustable means carried by the casing to rotate said reflector and adjustable means to actuate the vertically adjustable support longitudinally of the casing to tilt the reflector. 95

2. In a head light, a casing, a reflector within the casing, a vertically disposed threaded rod carried by the casing, said rod being pivotally connected to said reflector, 105 said casing being provided with an elongated slot for the passage therethrough of said rod, thumb nuts carried by the rod located on opposite sides of the slotted portion of the casing, means to rotate said reflector upon said rod, a block slidably engaging said vertically disposed rod, a second horizontally disposed rod pivotally connected at one end thereof to said block, and means to actuate said horizontally disposed 115 rod to move the vertical rod longitudinally of the elongated slot in the casing.

3. In a head light, a casing, a reflector within the casing, a vertically disposed threaded rod carried by the casing, said rod 120 being pivotally connected to said reflector, said casing being provided with an elongated slot for the passage therethrough of said rod, thumb nuts carried by the rod located on opposite sides of the slotted portion 125 of the casing, means to rotate said reflector upon said rod, a block slidably engaging said vertically disposed rod, a second horizontally disposed rod pivotally connected at one end thereof to said block, means to ac- 130

- tuate said horizontally disposed rod to move the vertical rod longitudinally of the elongated slot in the casing, and means to rotate said reflector upon said vertical rod.
- 5 4. In a head light, a casing, a reflector within the casing, said casing being provided with an elongated slot, a vertically disposed rod within the casing, said rod at one end being pivotally connected to said
- 10 reflector at one end, the opposite end of said rod passing through the elongated slot

and arranged for movement longitudinally thereof, fastening means associated with the rod to engage said casing, and means to rotate said reflector upon said rod.

15

Signed at New York city, N. Y., this 29 day of Dec. 1919.
